UNITED STATES PATENT OFFICE.

HART HARRIS, OF WASHINGTON, PENNSYLVANIA, ASSIGNOR OF ONE-HALF
TO ROBERT LOWE, OF SAME PLACE.

GAGE-COCK.

SPECIFICATION forming part of Letters Patent No. 669,880, dated March 12, 1901.

Application filed June 23, 1900. Serial No. 21,344. (No model.)

To all whom it may concern:

Be it known that I, HART HARRIS, a citizen of the United States, residing at Washington, in the county of Washington and State of Pennsylvania, have invented a new and useful Gage-Cock, of which the following is a specification.

This invention relates to gage-cocks; and the object of the same is to provide a simple and effective construction wherein the valve is loosely connected to and removably held by the stem and adapted to be maintained in close relation to its seat by boiler-pressure, rotated regularly to establish communication between different portions of the cock or grind the seat, and drawn up entirely clear of the seat for blowing-out operations, the valve-stem being freely rotatable and slideable in the casing to permit the pursuance of the several movements set forth.

The invention consists in the construction and arrangement of the several parts, which will be more fully hereinafter described and claimed.

25 In the drawings, Figure 1 is a perspective view of a gage-cock embodying the features of the invention. Fig. 2 is a longitudinal vertical section of the same, showing the valve and stem in an elevated position in dotted lines. Fig. 3 is a perspective view of the valve and stem.

Similar numerals of reference are employed to indicate corresponding parts in the several views.

35 The numeral 1 designates a valve-casing having a chamber 2 therein and an attaching-neck 3, formed with a bore 4, communicating at opposite extremities, respectively, with the boiler and the said chamber. The lower portion of the chamber 2 is regularly formed to produce a seat 5, having a flat bottom 6, and eccentrically opening through the seat-bottom is an outlet bore or port 7, which depends through the lower reduced extremity 8 of the casing for an obvious purpose. The seat 5 is of less diametrical extent than the chamber 2, and therein is loosely and rotatably mounted a disk valve 9, having an upwardly-projecting bifurcated stud 10, in 50 which the lower reduced extremity 11 of a valve-stem 12 is fitted and loosely and re-

movably connected, the formation of the joint between the stem and valve being such as to cause the said valve to regularly respond to rotative movements of the stem 55 without lost motion. The valve-stem is freely slideable, as well as rotatable, in a cap 13, which is removably secured in the upper portion of the casing and forms the top wall for the chamber 2. The cap has an upwardly-projecting tubular extension 14 to give a long bearing to the stem, and the lower portion of the said extension is provided with flat faces, as at 15, for the application of a wrench or an analogous implement to secure 65 and remove the said cap, and the exterior of the upper portion of the extension is formed with screw-threads 16 to receive a stuffing-box 17, having a suitable packing therein to provide a steam-tight joint around the stem. 70 On the upper end of the stem a handle or key 18 is fastened for use in rotating and lifting the same and the valve, and to provide means for establishing communication between the chamber 2 and the bore 7 of the 75 reduced extremity of the casing the valve 9 has a port 19 eccentrically arranged therein, as clearly shown in Fig. 3.

The particular mode of applying this type of cock to a boiler is well understood, and 80 its individual operation only will be explained, as follows: When the valve 9 is turned by the stem 12 a sufficient distance in either direction, the port 19 in the valve will be caused to align with the upper terminal of the bore 7, and thereby communication will be set up between the chamber 2 and the said bore. When the valve is turned to close the bore 7, it will be held firmly down to its seat by the boiler-pressure, which 85 will influence it direct, and thus prevent leakage. If it be desired to blow out a boiler, the valve can be completely cleared from its seat by drawing upwardly on the stem, and, furthermore, the seat may be ground by exerting an exterior manual pressure on the stem and continually rotating the valve. The connection between the valve and stem is of a loose character, so that the valve may be firmly seated irrespective of grit or other 90 substance that may collect on the bottom 6 or other portion of the seat, and also the

said joint permits the valve to automatically conform to any irregularities in the seat that may arise from an unequal wear. As before indicated, however, the looseness of the joint 5 will not detract in the least from positively effecting a rotative movement of the valve to open or close communication between the several parts.

Having thus described the invention, what 10 is claimed as new is—

1. In a gage-cock, the combination of a casing having a seat, a valve rotatably and removably mounted on said seat, and a valve-stem slidably and rotatably disposed in said 15 casing and having its lower extremity loosely and removably connected to said valve.

2. In a gage-cock, the combination of a casing having a seat, a valve rotatably and removably mounted on said seat, and a smooth 20 valve-stem slidably and rotatably disposed

in said casing and having its inner end loosely and removably attached to the valve.

3. In a gage-cock, the combination of a casing having steam-conveying bores therein at an angle to each other and communicating 25 with a chamber, the lower part of the chamber being formed as a valve-seat, a valve rotatably and removably mounted on said seat and having a port therethrough, and a valve-stem slidably and rotatably disposed in said 30 casing and having its inner end loosely and removably attached to the valve.

In testimony that I claim the foregoing as my own I have hereto affixed my signature in the presence of two witnesses.

HART HARRIS.
